[57] CLAIM

The ornamental design for console for the operation of machinery, as shown and described.

DESCRIPTION

FIG. 1 is a side perspective view of a console for the operation of machinery showing our new design;

FIG. 2 is a side elevational view thereof, the opposite side elevational view being a mirror image;

FIG. 3 is a rear elevational view thereof;

FIG. 4 is a front elevational view thereof;

FIG. 5 is a top plan view thereof.

FIG. 1

FIG. 3

FIG. 2

FIG. 5

FIG. 4
